UNITED STATES PATENT OFFICE.

WILLIAM D. BLUDWORTH, OF SACRAMENTO, CALIFORNIA.

DESIGN FOR A PONY AND RIDER TOY.

Application filed May 8, 1925. Serial No. 13,376. Term of patent 14 years.

To all whom it may concern:

Be it known that I, WILLIAM D. BLUDWORTH, a citizen of the United States, residing at Sacramento, in the county of Sacramento and State of California, have invented a new, original, and ornamental Design for a Pony and Rider Toy, of which the following is a specification, reference being had to the accompanying drawing, forming part thereof, and in which

Fig. 1 is a side view of my toy showing my new design, and

Fig. 2 is a front end view of the same.

I claim:—

The ornamental design for a pony and rider toy, as shown.

WILLIAM D. BLUDWORTH.
